UNITED STATES PATENT OFFICE.

GEORG DRALLE, OF HAMBURG, GERMANY.

DESIGN FOR A PERFUMERY-BOTTLE.

44,365.

Specification for Design.

Patented July 22, 1913.

Application filed April 8, 1913. Serial No. 759,782. Term of patent 3½ years.

To all whom it may concern:

Be it known that I, GEORG DRALLE, a subject of the German Empire, and a resident of Hamburg, Germany, have invented a new, original, and ornamental Design for Perfumery-Bottles, of which the following is a specification, reference being had to the accompanying drawing, forming part thereof.

Figure 1 is a side elevation of a bottle, showing my new design. Fig. 2 is a corner

elevation thereof. Fig. 3 is a plan view from above. Fig. 4 is a plan view from below.

I claim:

The ornamental design for a perfumery bottle, as shown.

GEORG DRALLE.

Witnesses:

ERNEST H. L. MUMMENHOFF,
IDA CHRIST. HAERMAN.
